CLAIM

The ornamental design for headphones, as shown and described.

DESCRIPTION

FIG. 1 is a front and left side perspective view of headphones showing my new design, with the cable cords shown as broken off for convenience of illustration;

FIG. 2 is a front elevational view with the cables shown partially broken off for convenience of illustration;

FIG. 3 is a left side elevational view thereof;

FIG. 4 is a top plan view thereof;

FIG. 5 is a bottom plan view thereof;

FIG. 6 is a fragmentary elevational view thereof taken in the position of arrows 6—6 in FIG. 2;

FIG. 7 is a top plan view of the single pin plug with the attached cord shown as broken off;

FIG. 8 is a side elevational view thereof;

FIG. 9 is a bottom plan view thereof;

FIG. 10 is a top plan view thereof;

FIG. 11 is a view like FIG. 1 with the cables detached;

FIG. 12 is a top plan view of a dual pin plug with the attached cord shown as broken off;

FIG. 13 is a side elevational view thereof;

FIG. 14 is a bottom plan view thereof; and

FIG. 15 is a top plan view thereof.
